UNITED STATES PATENT OFFICE.

HOWARD J. MURRAY, OF BROOKLYN, NEW YORK.

GEAR-SHIFTING DEVICE.

1,268,266.

Specification of Letters Patent. Patented June 4, 1918.

Application filed November 11, 1914. Serial No. 871,439.

To all whom it may concern:

Be it known that I, HOWARD J. MURRAY, a citizen of the United States, and resident of the borough of Brooklyn, in the county 5 of Kings and State of New York, have invented certain new and useful Improvements in Gear-Shifting Devices, of which the following is a specification.

My invention relates to an electric control for use in connection with mechanically actuated gear shifting and similar mechanism of the type which depends for its operation upon the selective throw of certain controlling members.

15 One of the objects of the invention is to provide a simple form of control which will positively move the desired controlling member on the closing of a suitable electric switch with the least expenditure of energy, 20 electrical or mechanical, and which will automatically return the parts to a neutral or safety position in case of short circuiting or other functional derangement of the parts.

A further object is to provide a device of 25 the above indicated character which may be momentarily coupled with some continuously driven part for a time sufficient to make the desired shift of the controlling member.

30 Various other objects and advantages of the invention will be in part obvious from an inspection of the accompanying drawings and in part will be more fully set forth in the following particular description of 35 one form of mechanism embodying my invention, and the invention also consists in certain new and novel features of construction and combination of parts hereinafter set forth and claimed.

40 In the drawings:

Figure 1 is a plan view of a portion of one form of my invention showing a device of the magnetic locking type with parts of the casing broken away to show details of 45 construction;

Figs. 2 and 3 are respectively a long sectional view taken on the line 2—2 and a transverse sectional view taken on the line 3—3 of Fig. 1;

50 Fig. 4 is a diagrammatic view of the

mechanism of Fig. 1 together with its electrical connections;

Fig. 5 is a side elevation of a friction clutch used in connection with the device;

Fig. 6 is a sectional view taken diametrically through a preferred form of control switch;

Fig. 7 is a view similar to Fig. 1 showing in a modified form of the invention one form of mechanical locking device.

Figs. 8 and 9 are respectively a longitudinal sectional view taken on the line 8—8 and a transverse sectional view taken on the line 9—9 of the modified form of the invention shown in Fig. 7; and

Fig. 10 is a diagrammatic view of the mechanism of Fig. 7 together with its electrical connections.

As the invention may be admirably embodied in a gear shifting mechanism for automobiles it will be described in connection with such a device but it will be readily appreciated that the invention is not so limited but may be utilized wherever an electrically controlled selective means is operated from a suitable source of mechanical power.

In the drawings there is illustrated a mechanism containing casing 4 which may be mounted at any suitable place on an automobile and which has a pair of parallelly disposed gear shifting rods 5 and 6 extending into opposite ends of the same and mounted for reciprocatory movement in either longitudinal direction to shift the different speed gears usual in automobile construction. While two rods are illustrated the description of any one rod and its connected parts will cover any number of such rods. The central portion of each rod within the casing has an electromagnet containing

90 box 7, preferably in the form of a hollow casing, fixed to the rod and forming the inner stop for strong balancing springs 8 and 9 which act to return the rod to its normal inoperative position when free of 95 the locking means hereinafter described. The box contains two stop electromagnets 10 and 11 of the plunger type disposed longitudinally of the rod, the plungers 12 and 13 of which are normally held depressed by

low the top plate 14 of the box by means of springs 15. In the form shown in Figs. 1 to 3 a locking electromagnet 16 is positioned between the stop electromagnets and has a plunger 17 projected by means of the spring 18 through the bottom plate of the box 7 to slide on and off the ends of a locking bar 19 which is fastened to the casing 4. A reciprocating power member 20 has its opposite ends guided in tracks 21 on the inner longitudinal side of the casing 4 for movement longitudinally of the rods 5 and 6 and across the top of the boxes 7 fixed to these rods.

15 The plungers 12 and 13 are arranged so that when either one is projected above the top plate 14 by the passage of current through either of the electromagnets, the projected plunger will be in the path of travel and in advance of the member 20 to form a stop or catch for connecting the member and rod.

20 The member 20 is reciprocated in any suitable manner and is shown to be in the form of a cross head actuated by means of a connecting link 22 and crank 23 driven from a shaft 24 which is suitably journaled in the casing 4.

25 The shaft may be connected with any motor driven mechanism as by means of a flexible shaft 25. In automobile construction it has been found convenient to attach the generator shaft to the flexible shaft thus permitting the convenient locating of the box.

30 In connection with the installation of the device, on such devices as automobiles, a friction clutch 26, of any conventional form now used on automobile construction and one form of which is illustrated in Fig. 5, is inserted at some suitable place in the line of the flexible shaft. This clutch is so controlled by a suitable pedal 27 that the crank will have no motion except when the usual 35 engine clutch is "out," when the clutch is "in" the faces 28 will be apart and no power transmitted. For the purpose of this disclosure it is to be understood that the pedal 27 may be the usual clutch control pedal found on automobile construction.

40 The movement of the rod into its locked position may be used to interrupt automatically the electric current through the electromagnets 10 and 11 and for this purpose the plunger 17 of the locking electromagnets is provided with an insulated head 29 adapted when the plunger is moved into its locking position to engage one of the pair of normally closed contacts 30 constituting a circuit breaker to break the circuit through the stop electromagnets.

45 The supply of current to the several electromagnets is controlled by a switch 31 which may be mounted on top of the steer-

50 ing wheel of the vehicle or in any other position convenient to the operator. The switch used in connection with the form illustrated in Figs. 4 and 6 is of the two way type and includes a lever 32 constituting the hand control of the switch which lever is pivoted 55 at one end for universal movement and a segmental contact plate 34 is disposed concentrically of the pivoted end of the lever preferably on the under side of the cover to the switch box 35. A series of contacts in 60 this embodiment of the invention shown to be five in number and lettered progressively R, N, 1, 2 and 3 to indicate respectively reverse, neutral, first, second and third speed are disposed in an arc to the outside of the 65 plate and in position to have the circuit completed therethrough when the lever is brought into engagement therewith and so spaced from the plate 34 that the lever is out of contact with the plate when in engagement with any other contacts.

70 A suitable source of electric energy 35 is connected through the conductors 36 with the pair of locking electromagnets and the circuit including these electromagnets contains a cut out switch 37 so connected with the engine clutch and with the pedal controlled clutch 26 that the cut out switch is in circuit closing position only when the clutch is "out." This circuit also includes 75 the main snap switch 38 the two locking electromagnets in parallel, cut out switch 37, plate 34, lever 32 and the source.

80 Current is supplied to the stop electromagnets at adjacent ends of each rod by means of a conductor 39 which leads from one of the contacts, such as R to another of the contacts, such as 1, and similarly current is lead through the pair of electromagnets at the other end of the box by conductor 40, 85 opposite ends of which lead from another pair of contacts, such as 2 and 3.

90 The circuit breaker 30 of one of the rods is positioned in a conductor 41 connecting the conductor 39 with the conductor 36 and the other circuit breaker 30 is in a conductor 42 which connects conductors 36 and 40.

95 In the form illustrated in Fig. 10 only four stop electromagnets are needed to provide the four shifts, the locking electromagnets being omitted together with the contact plate 34. In this form a conductor 43 leads from the source to one side of each of the electromagnets and separate conductors lead from the opposite side of each of 100 the electromagnets to the contacts R, 1, 2 and 3.

105 The locking device in this form is provided by the spring pressed catches 44 mounted on the top of the casing 4 at the 110 limit of movement of the plungers 12 and 13 when pushed thereto by the members 20. These catches or bolts are positioned in hous-

ings depending from the cover plate of the casing 4 and normally project therefrom by means of springs 44^a. The end of the catches depending from the cover plate of the casing 5 4 and normally projected therefrom by means of springs 44^a. The ends of the bolts are beveled on the side facing the member, so that the plungers when in raised position may pass under either of the bolts into a 10 locked position and the rod will thus be held in its shifted position as long as the electromagnets having the locking plunger is energized.

The different conductors are preferably 15 contained in a cable 46 leading from the switch box 35 to a multiple plug 47 which fits into a jack strip on the side of the casing 4 so that it can be conveniently detached.

To indicate what set of gears are connected a lamp indicator 48 may be positioned at some suitable place on the automobile with each lamp thereof in a circuit shunted off the contacts R, N, 1, 2 and 3 so that the closing of the circuit through any 25 of the contacts will light the corresponding designated lamp.

In operation and with the several parts in the position shown and with the clutch out and contact closed, the cross head may be 30 considered as reciprocating under the action of the power supplied to the shaft. The switch lever may then be moved to engage any of the contacts as for instance to engage the contact 1, as shown in Fig. 4. This will 35 complete the circuit from the source through the closed circuit breakers, through one of the stop electromagnets, contact 1, the lever and back to the source.

The passage of current will project the 40 plunger of one of the stop electromagnets into the path of the reciprocating member so as to cause this member to engage the projected end of the plunger and to act thereon to slide the rod supporting the same longitudinally for a distance equal to and in the direction of movement of the stroke of this member. It will be thus seen that the slide 45 20 may slide back and forth without moving any of the rods but as soon as one of the 50 plungers is projected into the path of the moving slide, the plunger is engaged and its attached rod shifted to make the desired 55 shift in the arrangements of the gears or other mechanism controlled by the shifting of the rods 5, 6. During this sliding movement the plunger of the locking electromagnet on this shifted rod is in engagement with the locking bar under the action of the spring but when it reaches its locking position at the end of the bar it will be forced 60 into a lowered position at the end of the locking bar 19. This dropping of the plunger automatically interrupts the circuit through the contacts 30 and the current will

then be completed from the source through 65 the locking magnet on the shifted rod. This breaking of the circuit through contacts 30 further acts to intercept the current through the stop electromagnet, thus permitting the spring acting on the plunger of the stop 70 electromagnet to withdraw the same from the path of the reciprocating member.

To withdraw the plunger of the locking electromagnet from its locking position the lever is raised out of engagement with its 75 lettered contacts and into engagement with the plate 34. The current will thus be completed from the source through the locking electromagnet, the clutch switch, contact plate, and lever back to the source. The 80 completion of the current through the electromagnet 16 will energize the same and act on the plunger 17 to raise the same clear of the locking bar 19. Releasing the locking of the shifted rod permits the balancing 85 spring under tension to return the rod and its attached electromagnet box back to its normal inoperative position.

In the form shown in Fig. 10 the lever may be moved to engage any of the contacts 90 as the one lettered "1" in which the circuit is completed from the source through the conductor 43, the right hand electromagnet 11, contact 1, lever and conductor back to the source. This will raise the plunger of 95 the energized electromagnet as has been previously described, to permit the reciprocating member to shift the rod in which position it is locked by the spring pressed catch 44. The rod will be maintained, locked in 100 its shifted position as long as current flows through the electromagnet. Raising the lever out of engagement with the contacts 105 interrupts the current through the electromagnet and permits the spring acting on the plunger to withdraw the same out of contact with the catch and thus permits the balancing springs 8 and 9 to return the rod to its normal position.

From this detailed tracing of one circuit 110 in each of the two forms illustrated it will be apparent from following the lines in Figs. 4 and 10 how the similar circuits are completed through the other electromagnets when the lever engages the different contacts.

A device of this character may be actuated from any convenient or continuously moving engine part and the only electric energy consumption in the system is that actually used 120 for a moment to shift the plungers of the locking and stop electromagnets in the form illustrated in Fig. 2. Even the form illustrated in Fig. 8 requires but little electric energy to maintain the plungers in their projected 125 position for the plungers are not required to do any work against resistance. Should the circuit controlling the electromagnets in this

latter form become short or open or if the battery should become discharged, the gear shifting rods will automatically return to their normal inoperative position and in this 5 way a safety device is provided.

It is understood that so long as any rod is shifted, *i. e.* any gear is in mesh, a mistake cannot be made as all of the magnet circuits are open until the shifted rod is returned to 10 its normal position.

Having thus described my invention, I claim:

1. In a device of the class described, the combination of a mechanism actuating rod, 15 a stop carried by said rod, electromagnetic means controlled from a distance for moving said stop to and from an operative position, a reciprocating power member movable parallel to the length of said rod and 20 adapted to engage said stop when in operative position thereby to shift the rod longitudinally into an operative position and means for automatically locking said rod in its shifted position.

2. In a device of the class described, the combination of a mechanism actuating rod, 25 a stop carried by said rod, electromagnetic means controlled from a distance for moving said stop to and from an operative position, a reciprocating power member movable parallel to the length of said rod and adapted to engage said stop when in operative position thereby to shift the rod longitudinally into an operative position, means 30 for automatically locking said rod in its shifted position and means engaging said rod tending to return the same to its normal inoperative position when unlocked.

3. In a device of the class described, the 40 combination of a mechanism actuating rod, a stop carried by said rod, a reciprocating power member movable parallel to the length of said rod and adapted to engage said stop to shift the rod longitudinally into an operative position, means for automatically locking said rod in its shifted 45 position, means engaging said rod tending to return the same to its normal inoperative position when unlocked and electrically controlled means for unlocking said rod.

4. In a device of the class described, the combination of a mechanism actuating rod, 50 a stop carried by said rod, a reciprocating power member movable parallel to the length of said rod and adapted to engage said stop to shift the rod longitudinally into an operative position, means for automatically locking said rod in its shifted 55 position and electrically actuated means for moving said stop relative to the path of movement of the reciprocating member.

5. In a device of the class described, the combination of a mechanism actuating rod mounted for longitudinal movement in

either direction from a normal position, a 65 pair of spaced apart stops carried by said rod, a power member mounted for reciprocatory movement parallel to said rod and selective means for positioning either one of said stops in the path of movement of 70 said power member thereby to shift the rod in the direction of movement of said member engaging the stop.

6. In a device of the class described, the combination of a mechanism actuating rod, 75 a mechanically actuated member, means engaging said member designed to move the same for a distance greater than the maximum distance necessary to effect the actuation of the rod, and electrically controlled 80 means carried by said rod adapted to form a connection between said member and rod whereby said rod is shifted by the movement of said member and locking means for holding said rod in its shifted position. 85

7. In a device of the class described, the combination of a mechanism actuating rod, a mechanically actuated member, a continuously moving power device operatively connected to said member, an electrically 90 controlled means carried by said rod adapted to form a connection between said member and rod whereby said rod is shifted by the movement of said member, locking means for holding said rod in its shifted 95 position and means for moving said locking means into an inoperative position.

8. In a device of the class described, the combination of a mechanism actuating rod, a continuously moving member, an electrically 100 controlled means forming a connection between said rod and member whereby said rod may be shifted at will by the movement of said moving member into a position beyond the control of said member and automatically actuated means for locking 105 said rod in its shifted position independent of the moving member.

9. In a device of the class described, the combination of a mechanism actuating rod, 110 a mechanically actuated member, a power shaft operatively connected to said member and adapted to move the same continuously, an electrically controlled means forming a connection between said rod and member 115 whereby said rod may be shifted at will by the movement of said member, automatically actuated means for locking said rod in its shifted position and electrically controlled means for moving said locking 120 means into an unlocking position.

10. In a device of the class described, the combination of a mechanism actuating rod, a mechanically actuated member, an electrically controlled means forming a connection between said rod and member whereby said rod may be shifted at will by the movement of said member and means controlled 125

by the movement of the rod into its shifted position for interrupting the current through said electrically controlled means.

11. In a device of the class described, the combination with an actuating member, an actuated member, a pair of stop electromagnets each designed to connect said members and a locking electromagnet designed to lock one of said members, of an electric circuit including a source of electric energy, said locking electromagnet and a contact of a two way switch, said second circuit terminating in a pair of contacts and including a pair of stop electromagnets in series, and a two-way switch adapted in one position to engage said first named contact to close the circuit through the locking electromagnet and in another position to engage one of the pair of contacts to close the circuit through its corresponding stop electromagnet.

12. In a device of the class described, the combination with an actuating member, an actuated member, a pair of stop electromagnets each designed to connect said members and a locking electromagnet designed to lock one of said members, of an electric circuit including a source of electric energy, said locking electromagnet and a contact of a two-way switch, a second circuit terminating in a pair of contacts and including said pair of stop electromagnets in series, a two-way switch adapted in one position to engage said first named contact to close the circuit through the locking electromagnet and in another position to engage one of the pair of contacts to close the circuit through its corresponding stop electromagnet and a normally closed circuit breaker connecting said circuits.

13. In a device of the class described, the combination with an actuating member, an actuated member and a pair of electromagnets designed to connect said members, of a circuit including a pair of contacts forming the terminal of said circuit and said pair of electromagnets disposed in series in said circuit, a source of electric energy, a conductor leading from one side of said source to the portion of the first named conductor connecting the electromagnets, a circuit switch adapted to engage either one of the pair of contacts and a con-

ductor leading from the other side of said source to said switch whereby moving the switch into one of the contacts will energize the corresponding electromagnet.

14. In a device of the class described, the combination with an actuating member, an actuated member and a pair of electromagnets designed to connect said members, of a circuit including a pair of contacts forming the terminal of said circuit and a pair of electromagnets disposed in series in said circuit, a source of electric energy, a conductor leading from one side of said source to the portion of the first named conductor connecting the electromagnets, a circuit switch adapted to engage either one of the pair of contacts, a conductor leading from the other side of said source to said switch whereby moving the switch into one of the contacts will energize the corresponding electromagnet, and a circuit shunted from each of said pair of contacts, an indicator in each of said circuits actuated by the completion of the circuit through either of the said contacts.

15. In a device of the class described, the combination of a plurality of mechanism shifting rods, a mechanically driven reciprocating member, electrically controlled selective means designed to be disposed in the path of travel of the reciprocating member for connecting one of said rods with said reciprocating member to shift the rod in the desired direction.

16. In a device of the class described, the combination of a mechanism controlling rod adapted to be shifted longitudinally, a continuously reciprocating power member, electrically controlled means for connecting said rod with said member whereby said rod will travel with said member to actuate the mechanism controlled thereby, said member being free to move independently of the position of the rod whereby said member may be driven from a continuously moving element of an engine.

Signed at New York city, in the county of New York, and State of New York, this ninth day of November, A. D. 1914.
